UNITED STATES PATENT OFFICE.

GEORGE W. WOOD, OF INDIANAPOLIS, INDIANA.

SHIRT-CUFF.

1,081,802.

Specification of Letters Patent.

Patented Dec. 16, 1913.

Application filed January 15, 1912. Serial No. 671,233.

To all whom it may concern:

Be it known that I, GEORGE W. WOOD, a citizen of the United States, and a resident of Indianapolis, county of Marion, and 5 State of Indiana, have invented a certain useful Shirt-Cuff; and I do hereby declare that the following is a full, clear, and exact description thereof, reference being had to the accompanying drawings.

10 The object of this invention is to provide a detachable cuff for shirt sleeves and the like, which has the appearance of an attached cuff or integral with the sleeve.

In addition to the foregoing there is the 15 further object of providing an arrangement for the very easy and quick placing and removal of the cuff and for safely and satisfactorily holding the cuff when in place.

The nature of the invention will be understood from the accompanying drawings and the following description and claims.

In the drawings, Figure 1 is a side elevation of a portion of a shirt sleeve with the cuff in place thereon. Fig. 2 is an elevation 25 of one end of the shirt sleeve and the band thereon with the cuff removed. Fig. 3 is the same as Fig. 1, showing the cuff while it is being put on the shirt sleeve.

There is shown in the drawings a shirt 30 sleeve 10 having a band 11 stitched thereto and said band has its ends provided with button holes 12 for a button 13. The ends of the band 11, when buttoned, are placed against each other so as to be coterminous 35 and not to overlap and so that the band when thus buttoned, will not be round as it is when the ends overlap each other. The ends of the band 11 are provided with a V-shaped notch 14 suitably stitched so as to be 40 strong and projecting inwardly and located preferably near the outer edge of the band. Thus when the band is buttoned and secured as above explained, the notches of the two ends will register with each other and 45 thus the two ends of the band fitting flat against each other and held by the button 13, will form a rigid structure, when laundered, and are provided with the notches 14 so as to leave near the outer edge projections 50 15, as seen in Fig. 2.

The cuff 16 has in each end button holes 17 through which cuff buttons 18 extend, said cuff 16 being arranged in the same position as the band 11 when fastened. The cuff 55 has no other holes through it than the one for the cuff button 18, as it is not fastened

to the band of the shirt sleeve by any button. The button 13 fits only in the sleeve band and the button 18 only in the cuff. No button goes through both the cuff and the 60 sleeve band, but the cuff is held in position by the notch 14 with the projection 15 on the outer side and the projection on the inner side, and also by reason of the cuff being a comparatively snug fit on the band 11. 65 The sleeve band is made relatively large so as to fit snugly in the cuff. The buttoned end of the cuff is first put in place with the cuff button projecting through the notch 14 of the sleeve band and then the upper part 70 of the cuff is pressed back over the band and the relative size of the cuff and band should be such that some little force would be required to push the upper part of the cuff back over the band, in the position shown 75 in Fig. 1. The tight fit thus resulting will hold the cuff in place so that it would not rattle and it would not come off. Of course, the lower part cannot come off on account of the projection 15 of the sleeve band and 80 the upper part should fit snug enough so that the cuff would not escape from the band. When it is desired to remove the cuff, the upper part is forcibly drawn outwardly to the position shown in Fig. 3, and 85 then it can fall away from the notched side of the sleeve band. This makes the cuff readily attachable and detachable and firmly holds it in place while it is being worn and it is very readily detached because it is not necessary to insert the cuff 90 button through the sleeve band and since the sleeve band is the same shape as the cuff and they both lie tightly together, they have the appearance and feeling of an integral 95 cuff construction. By placing the cuff button-holes centrally, the cuff is readily reversible.

I claim as my invention:

1. The combination of a sleeve band having at its ends opposite button holes whereby said ends may be united so that they will be flush with each other and corresponding V-shaped notches in the ends of said band, and a cuff adapted to fit snugly on said band 105 and provided with opposite button-holes in the ends thereof and midway between the edges of the cuff so that the cuff button which extends through the button holes will also extend through the notches in the ends 110 of said sleeve band.

2. The combination of a sleeve band hav-

ing at its ends opposite button holes whereby said ends may be united so that they will be flush with each other and corresponding notches in the ends of said band, and a cuff 5 adapted to fit snugly on said band and provided with opposite button holes through its ends so that the cuff button which extends through said button holes will also extend through the corresponding notches

in the ends of the band near the outer edge 10 of the band.

In testimony whereof, I have hereunto affixed my signature in the presence of the witness herein named.

GEORGE W. WOOD.
